UNITED STATES PATENT OFFICE.

JAMES HAMILTON BALLENTINE, OF HUNTSVILLE, ALABAMA.

NUT LOCK.

1,406,956.

Specification of Letters Patent. Patented Feb. 14, 1922.

Application filed March 29, 1919. Serial No. 286,197.

To all whom it may concern:

Be it known that I, JAMES HAMILTON BALLENTINE, a citizen of the United States, residing at Huntsville, in the county of

5 Madison and State of Alabama, have invented certain new and useful Improvements in Nut Locks; and I do hereby declare the following to be a full, clear, and exact description of the invention, such as 10 will enable others skilled in the art to which it appertains to make and use the same.

This invention relates to improvements in nut-locks of the general type wherein are 15 employed a bolt, with its thread cut, intersected, or interrupted by a longitudinal groove, a nut preferably of the castellated type, and interlocking means therebetween, said means also providing for the locking 20 of a washer therewith, if the use of such be desired. The invention in its simpler form provides for the locking of a nut alone upon a bolt, as in the use of the same without a washer.

25 Among various objects of my invention, it may be mentioned that the nut is most effectively secured or locked on its bolt as against turning or being displaced from a jarring action, or otherwise inadvertently 30 displaced; that the locking or interlocking means are simple, of few elements and inexpensive of manufacture; that its elements are adapted to be readily and quickly assembled and disassembled; that said elements 35 are capable of being applied in either of two ways in effecting the assembling thereof, as conditions may suggest; and that the aforesaid objects may be carried out in a simple and effective way, and with facility.

40 The invention consists, therefore, of certain instrumentalities and features of construction of parts substantially as herein-after more fully disclosed and pointed out by the appended claims,

45 In the accompanying drawings is illustrated the preferred embodiment of my invention (inclusive of a preferred modification thereof), wherein it will be seen and understood that various changes and modifications which may fall within the scope 50 or breadth of the claims, may be made as to the detailed construction and arrangement of parts without departing from the spirit of my invention.

55 In the drawings:

Figure 1 is a side elevation of one form

of my invention with the elements thereof in assembled and interlocked position.

Figure 2 is a central longitudinal section thereof.

Figure 3 is a transverse section taken on the line 3—3 of Fig. 1, viewing in the direction of the arrow.

Figure 4 is also a transverse section, taken on the line 4—4 of Figure 1, parts being 65 broken away to disclose the portion of the key within the bolt and the lug or head of the key within the annular groove in the inner face of the nut.

Figure 5 is a side view of my nut-lock, 70 elements or parts being broken away, showing the key or pin having its head received by a notch or slot in the washer instead of within an annular groove in the nut, as described above.

In carrying out my invention, referring now particularly to Figures 1 and 2, I employ a bolt 1 threaded as usual for a portion of its length, and in said bolt is provided a longitudinal slot or key-way 2 opening out 80 clear through the outer or unheaded end of the bolt. The slot or key-way 2 cuts, intercepts or interrupts the screw-threaded surface of the bolt, preferably nearly the entire length thereof, its inner extremity 85 terminating adjacent the unthreaded portion, or what may be termed the shank of the bolt, the length of the slot, of course, being only a matter of expediency.

Another element of the invention consists 90 of preferably what is usually termed a castellated nut 3, which is threaded to be readily run on and off the bolt, and is counterbored to provide an annular groove 4 in its inner face, the purpose of which will 95 be apparent presently. In lieu of the castellated nut, any other type of nut, of hexagonal or other annular peripheral outline and notched or roughened or corrugated in its outer face, would serve my purpose, 100 as is obvious.

Also a further element hereof consists of a key or pin 5, preferably of malleable or bendable metal and of a predetermined 105 length and having its head 6 at a right-angle to the body portion thereof, the opposite or inner end of said pin or key being chamfered, beveled, or tapered, as at 7, with the inclination or slant presented towards the axial line of the bolt, with which as later 110 is shown, it cooperates. The pin or key 5 is so formed and of such general outlines as to

admit of its being readily inserted or slipped into the slot or key-way 2 of the bolt 1 and to lie therein bodily, out of contact with the nut. This is done, as before indicated, with its beveled or chamfered surface disposed next to the axial line of the bolt, and its head 6 received within the groove or slot 4 of the nut and in forcible engagement with one wall of said slot when the nut is screwed 10 to final locked position and the projecting portion of the pin is bent outwardly upon the nut as clearly disclosed, particularly by Figure 1.

It is observed that by reason of the pin or key being attenuated by being chamfered at one end, as described, the operation of bending it is facilitated and effected with less liability of breakage as pressure is applied thereto in effecting said bending operation, 20 the pin or key being caused to conform to a curved line as it is being bent from, and resting upon the nut as a fulcrum, in aiding such bending or curving operation. It is further observed that should it be required 25 to initially insert the key into the slot in the bolt, as in inserting it from the inner face of the nut and after partially running or screwing the nut upon the bolt and before screwing it to final position, as may be 30 found expedient under certain conditions, this may be done as follows: The key having been inserted within the bolt-slot, with its chamfer 7 presented towards the bottom of the bolt-slot, by inserting a suitable instrument 35 in contact with the chamfer or attenuated end of the key, and then suitably prying upon said instrument and further running the nut upon the bolt, as above indicated, the chamfered end portion of the key

may be withdrawn from the bolt-slot and be 40 bent upon the nut to locked position.

In the form of my invention as disclosed by Figure 5, the nut 3 is devoid of the annular groove 4, and to the bolt 1 is applied a washer 8 interposed between the nut and the object through which is passed the bolt for its retention in place. The washer 8 has a slot or notch 9 and with this notch or slot is engaged the head 6 of the pin or key 5, inserted into the bolt-slot and engaged with 50 the nut whereby the key, washer and nut, all will be interlocked together and upon the bolt.

It is considered from the foregoing that the structure, operation and purposes of my 55 invention will be readily understood.

Having thus described my invention, what I claim as new and desire to secure by Letters Patent is:

A nut-lock including a bolt having a longitudinal slot severing the bolt threads throughout, a threaded nut applied to said bolt and having an annular recess in the wall of its bolt-receiving opening, a key provided with a laterally extended head adapted to be received by the annular recess of the nut, the opposite attenuated end of said key extending beyond the nut whereby said outer end of the key may be readily bent along the outer face of the nut and thence 70 extended inwardly in contact with the lateral edge or side of said nut, thereby effecting an interlocking connection between said nut and bolt.

In testimony whereof, I affix my signature.

JAMES HAMILTON BALLENTINE.
